UNITED STATES PATENT OFFICE

DAVID C. PRINCE, OF SCHENECTADY, NEW YORK, ASSIGNOR TO GENERAL ELECTRIC COMPANY, A CORPORATION OF NEW YORK

HIGH VACUUM FUSE

Application filed March 23, 1928, Serial No. 264,117. Renewed July 14, 1932.

My invention relates to high vacuum fuses for interrupting electric circuits, and more particularly to improvements which facilitate the production of the desired maintainable high vacuum and which are of particular advantage in the manufacture of such fuses for controlling circuits which carry considerable current.

In a copending joint application of Bert-
10 ram Wellman and myself, Serial No. 264,113, filed concurrently herewith and a divisional application thereof, Serial No. 379,976, filed July 22, 1929, both assigned to the same assignee as the present application, the principles of construction and the mode of operation in alternating and direct current circuits
15 of fuses comprising a fuse link mounted between terminals spaced apart and located in a container or vessel exhausted to have an exceedingly high and maintainable vacuum are disclosed, and such fuses are broadly claimed in the aforesaid applications.

One of the main objects of my present invention is to provide a construction for high
20 vacuum fuses which shall be simple and rugged and which shall particularly facilitate the manufacture of such fuses for circuits of considerable current capacity, although certain features of the construction are advantageous also in the manufacture of fuses
25 in the smaller sizes.

My invention will be better understood from the following description when considered in connection with the accompanying
30 drawing, and its scope will be pointed out in the appended claims.

In the accompanying drawing Fig. 1 represents one embodiment of my invention, Fig. 2 represents the fuse of Fig. 1 as applied to protection of a potential transformer, Fig. 3 diagrammatically represents a modification utilizing several fuse links in parallel, Fig. 4 represents a variation of the construction of
45 Fig. 3, Fig. 5 represents an arrangement for securing equal division of current through several fuses or fuse links in parallel, Fig. 6 shows a detail of a modified form of fuse terminal utilizing the principles of my invention and Figs. 7 and 8 diagrammatically rep-

resent particular applications of the fuse to electric circuits.

In order to secure the desired functions and results above outlined it is important that the vacuum be extremely high. The better the 55 vacuum the better the fuse will operate. It should be better than a small fraction of a micron (thousandth of a millimeter). Satisfactory operation can be secured with a vacuum of the order of .01 to .001 micron, but as 60 above stated the best vacuum possible is desired and the best vacuum it is economically practicable to obtain should be had.

It is important to deprive the walls of the fuse vessel of occluded gases and to free the 65 fuse link and all metal parts within the vessel of such gases. The best technique for obtaining a maintainable high vacuum should therefore be used. In accordance with my invention evacuation to the proper degree of 70 vacuum is facilitated.

Referring to Fig. 1 the fuse link 1 is supported between spaced terminals 3 and 4 in the vessel 5. The vessel may be made of suitable glass, or quartz or of metal with 75 suitable provisions for insulating the conducting parts therefrom. The drawing shows, by way of example, a vessel with a central bulb in which the fuse link is located.

In the arrangement illustrated the fuse 80 supporting terminals 3 and 4 are mounted at the end of the reentrant or stem portions 6 and 7 of the vessel. In accordance with my invention I make the terminal members in the form of loops. In Fig. 1 they are shaped 85 like a hair-pin. The respective ends of the loop 3 are secured to leading-in conductors 8 and 9, and the ends of loop 4 are secured to leading-in wires 10 and 11. The leading-in wires may be sealed in the stems 6, and 7 90 of a glass vessel by a pinch seal. Suitable conductors which will make a vacuum tight seal with glass may be used. One example of such a conductor is disclosed in Letters Patent to Fink No. 1,498,908 dated June 24, 95 1924. My loop terminal makes such pinch seals easier to use since each leading-in conductor need have but half the cross-sectional area that would be necessary for a single conductor carrying the same amount of current. 100

To protect the seals from damage from electron bombardment, it is preferable to provide suitable shields as shown at 12 and 13. These shields may be of relatively thin 5 nickel, copper or the like. These shields are spaced from the stems 6 and 7 and may be supported in any suitable manner. As indicated at 12' the shield 12 is supported by a small plate welded to the front of the shield 10 and to the end of the leading-in conductor 9. The leading-in conductor 8 extends through a hole in the front of the shield and may be insulated therefrom as for example by a glass tube as indicated at 12".

15 After the vessel has been exhausted and sealed off, the leading-in conductors 8, 9 and 10, 11 are connected to the respective outside fuse terminals by which the fuse is to be connected in the circuit to be protected. As indicated in Fig. 2 the fuse may be provided with metal caps which have extensions for mounting in fuse clips or the equivalent. The fuse caps may be suitably secured to the vessel, as by cement for example. Where a 20 glass vessel is sealed off at one end, as indicated at 2 in Fig. 1, for example, the fuse cap may protect the projection from breakage, when the fuse is handled.

One of the main advantages of the loop or 30 hair-pin shaped terminals is that they permit a large current to be passed through these terminals to heat them to a high temperature to drive off occluded gases during exhaust. While the terminal caps are off and the leading-in wires 8 and 9 separate, it is apparent 35 that any desired amount of current can be passed through these wires to heat the loop terminal 3. The loop terminal 4 can be similarly heated by a source connected to the leading-in wires 10 and 11. By connecting a 40 source of current to one of the conductors 8 or 9 and also to one of the conductors 10 or 11, a heating current may be passed through the fuse link 1 to drive off from it occluded 45 gases during the exhausting operation. During exhaust suitable means will be used to bake the occluded gas out of the inner walls of the vessel. Thin metal parts, such as the shields 12 and 13, for example, can be quite effectively heated by inducing high frequency 50 currents therein by suitable means examples of which are well known. Such heating by magnetic induction is disclosed, for example, in Letters Patent to Pratt No. 1,874,679 dated

55 April 12, 1921.

After the exhaust has been completed the leading-in wires 8 and 9 are connected to one of the fuse caps and the wires 10 and 11 to the other fuse cap. The current that the 60 fuse link carries when connected in circuit is therefore twice as great as that carried by either leg of either terminal loop. Without the loop or hair-pin construction it would be impossible to pass any more current through 65 the supporting terminals than could be car-

ried by the fuse link. If the terminals were small enough to be sufficiently heated by this current during exhaust, it would be apt to be destroyed when the fuse interrupted a circuit while in service. If made as large 70 as they should be to act as proper supports and terminals for the electron discharge, they could not be sufficiently heated during exhaust by the largest current the fuse link 75 could carry.

It is apparent therefore that the loop construction has important advantages both during the exhausting operation and during operation of the fuse in service.

While the loop construction greatly facilitates the final exhaust of the vessel, it is very desirable thoroughly to de-gas all heavy parts before assembling them in the tube for the final exhaust. As pointed out in Letters Patent to Langmuir No. 1,558,436, dated 85 October 20, 1925, after metal has been freed from occluded gas, reabsorption of gas will not readily take place in air or other gases. This fact makes it advisable to pre-de-gas 90 such parts since the operation can be carried out more advantageously before the parts are in the vessel.

While vessels of glass can be made for fuses of any voltage it is feasible and generally will be preferable for the larger current 95 moderate voltage fuses to use vessels of metal with suitable seals and insulating means for the conductors which lead into the vessel. For very high voltage fuses, for example 100 fuses for the highest present day commercial voltages which are about 220,000 volts, the size of the fuse vessel is determined principally by the creeping or striking voltage which tends to make the fuse flash outside of the vessel. The use of metal vessels for such voltages results therefore in an increase in the 105 size of the devices whereas by using vessels of insulating material and submerging the entire device in oil so as to provide a high resistance against arc-over on the outside, the 110 device can be made considerably smaller.

The technique of providing suitable seals between large metal parts and glass is now known to those skilled in the art so that these 115 features do not present any unsolved problem where large leading-in conductors or relatively large metal vessels are to be used. Examples of such seals are shown in Letters Patent to Krueh et al. No. 1,564,690, December 8, 1925, and to Housekeeper No. 1,294,466, 120 February 18, 1919.

The fuse link 1 as heretofore indicated should be very thoroughly freed from occluded gases. This is particularly important 125 because of the fact that the fuse link may not only be raised to a high temperature when the fuse is carrying a large current but when the fuse breaks the circuit it is melted and vaporized. Tungsten has been found to be a suitable metal for the fuse link, but other 130

5 fuse metals may be used so long as the fuse link is mechanically satisfactory and does not produce a sufficient amount of gas when volatilized to reduce the insulating properties of the high vacuum dielectric.

10 The design and construction of the vessel and the mountings for the fuse link should be such that no part of the fuse or its supporting terminals can at any time during 15 normal operation or blowing of the fuse come too close to or touch the walls of the vessel. If such contact should occur it may impair the vacuum without breaking the envelope because the hot metal will cause the walls 20 of a glass vessel, for example, to evolve gas. Or the vessel may be cracked by the hot metal or may be punctured due to high potential gradients in the glass due to the wire point against it. In either event the vacuum is impaired and its dielectric strength lost.

25 The distance between the fuse terminals 3 and 4 can be made relatively small so that a short fuse link can be used. This reduces the amount of gas and metal vapor which may be evolved when the fuse blows and simplifies the problem of preventing contact with the wall of the vessel. A sufficient idea of the size of the device may be had from the fact that with a bulb 5 inches in diameter 30 and a fuse link of the order of 1½ inches in length a current of over 400 amperes has been successfully interrupted at 13,200 volts. The fuse vessel could probably be made still smaller for such service but the example given is 35 sufficient to indicate the size of the vessel required for lower voltages as well as higher voltages.

40 Experience with fuses of the high vacuum type described will enable one to determine from the appearance of a fuse when a predetermined testing current is passed through it, whether or not the vacuum is of the high order desired before the fuse is put into service on a line. If desired, however, any well 45 known method of testing such a fuse may be employed to determine whether or not the vacuum has been impaired or is satisfactory.

50 While the principles of my invention enable fuses to be manufactured for the interruption of heavy currents on lines of high voltage and relatively large capacity the fuse may also be built in smaller sizes and for less severe service. Fuses for the primary circuits of potential transformers have presented 55 some difficulties in the past. For example, cases sometimes occur in which the fuse fails to clear the circuit when by some abnormal condition an excessive current is gradually developed although the circuit 60 may be satisfactorily cleared in case of a short circuit on the potential transformer.

65 In Fig. 2 I have represented a fuse embodying my invention applied to the protection of such potential transformers. The fuse 14 is shown in series with the primary

winding 15 of the potential transformer. The secondary 16 of the transformer is indicated as connected to an instrument 17 such as a voltmeter or relay for example. In series with the fuse and the primary winding 70 15 a resistance 18 may be used. The line conductors 19 and 20 indicate any suitable source across which the potential transformer is connected. In this class of service the duty of the fuse is limited by reason of the fact 75 that the resistance 18 limits the amount of current which can flow even with the transformer 15, 16 short circuited.

In accordance with my invention it is feasible to mount several fuse links in parallel 80 within the fuse vessel. An example of such a construction is diagrammatically indicated in Fig. 3 in which four fuse links 21, 22, 23 and 24 are mounted in parallel between the terminal members 25 and 26 which correspond to the members 3 and 4 of Fig. 1. The leading-in conductors 27 and 28 enable a heavy local heating current to be passed through the two sides of the ring loop terminal 25 to bring the metal to the temperature necessary to drive off occluded gases even though the member be of relatively heavy stock. Similarly the leading-in conductors 29 and 30 permit heating current to be passed through the terminal ring or loop 26. Current may also be passed through the several 90 fuse links in parallel in the manner described in connection with passing current through the fuse link 1 of Fig. 1 to provide the necessary heating during the exhausting operation. After the fuse has been sealed off the 95 leading-in conductors may be connected to suitable fuse caps or terminals as described in connection with Fig. 1 and illustrated in Fig. 2. In order that the current may be divided substantially equally between the several fuse wires when the fuse is in service the fuse wires or links should be connected to the terminals 25 and 26 at the proper symmetrical points in order that the resistance 100 drop in the conducting metal through which the current flows may be substantially equalized.

105 If desired additional leading-in conductors similar to conductors 27 and 28, for example, may be connected to the loop or ring terminal members between the other pair of fuses. As indicated in Fig. 3, leading-in conductor 27 is connected to the loop 25 between the fuse links 21 and 22, and the leading-in conductor 28 is connected to the loop between the fuse links 23 and 24. Additional leading-in conductors may be connected to the loop respectively between the fuse links 21 and 23, and 22 and 24.

110 It is apparent that the terminal members for plural link fuses may be mounted and connected in a number of different arrangements. Fig. 4 diagrammatically represents one such modified form of arrangement generally the same as that of Fig. 3. In this case 125 130

the terminal loops 31 and 32 are indicated generally as squares. The leading-in conductors 33 and 34 are indicated as joined to a conductor 35 which will lead to the outside 5 fuse terminal. Similar conductors are indicated at the other end of the device. It is to be understood that the conductors 33 and 34 are not thus connected together to the terminal 35 until the exhausting operation has 10 been completed since these conductors must be kept separate in order to enable the desired local heating current to be passed through the sides of the loop.

If desired, means may be readily provided 15 for insuring that while the fuse is in service the currents carried by the leads 27 and 28 and also 29 and 30 of Fig. 3, or the similar leads 33 and 34 of Fig. 4, shall be substantially equal. This may be done by connecting 20 these leading-in conductors to the opposite ends of a reactance device comprising a number of turns wound in the same direction on an iron core. The conductor which connects to the outside terminal of the fuse, for example terminal 35 of Fig. 4, will be connected 25 to the midpoint of such reactance so that the reactance device is between the fuse terminal and the leading-in conductors.

The principle of operation of such reactance devices will be understood from a consideration of Fig. 5. In Fig. 5 the current is intended to be equalized between four conductors 36, 37, 38 and 39 supplied from a source assumed to be connected to terminals 40 and 41. The conductor 40 is connected to the midpoint of a reactance device 42. Current passing through the conductor 40 to or from the midpoint of the reactance 42 tends to traverse the two sides of the 40 coil in equal amounts. When the current in one side tries to predominate over the current in the other side that current which tends to predominate is choked back and simultaneously a transformer action tends to 45 increase the current in the side where the current has the lower value. The reactance device 42 therefore tends to keep the current carried by the two wires 36 and 37 equal to that carried by the two wires 38 and 39. 50 In order to equalize the current between the wires 36 and 37, and 38 and 39, the conductors 43 and 44 are connected to the midpoints of similar reactance devices 45 and 46. While such reactance devices at only 55 one end of the conductors 36, 37, 38 and 39 may be adequate to equalize the current sufficiently, similar reactance devices 47, 48 and 49 may be provided at the other end of these conductors.

60 In applying the principle of equalization shown in Fig. 5 to equalize the current in the conductors 33 and 34 for example of Fig. 4, it will be apparent that the conductors 43 and 44 of Fig. 5 correspond to the conductors 33 and 34 of Fig. 4, and that the conductor

35 of Fig. 4 will, when such a reactance device is used, be connected to the midpoint of the reactance as the conductor 40 is connected in Fig. 5.

Instead of providing a plurality of fuse 70 links in the same vessel it is apparent that a plurality of separate fuse devices may be connected in parallel and that the current through the individual fuses may be equalized by the arrangement shown in Fig. 5. In 75 this figure each of the conductors 36, 37, 38 and 39 will correspond to an individual fuse. The reactance devices insure that the several fuses will divide the current substantially equally both during normal operation 80 and while the fuses are blowing thus securing a simultaneous blowing of all of the fuses and thereby reducing the duty on each individual fuse.

Fig. 6 represents a modified form of fuse 85 terminal embodying generally the same principles and advantages as the loop or hairpin terminal arrangement of Fig. 1. In this figure, one end of the fuse link is indicated at 50 and is represented as welded to the terminal 51 which is secured in any suitable manner to a leading-in conductor 52, a screw threaded engagement being shown for the purpose of illustration. This conductor 52 is properly sealed into the fuse vessel as 90 above described. In order to heat the fuse terminal 51 effectively to drive out the occluded gases during the exhausting operation, a coil 53 is provided inside the terminal 51, one end of this coil being connected 95 to the fuse terminal 51 and the other end being extended through and brought out at a suitable point at the side of the leading-in conductor 52 as indicated at 54. A heating current may be supplied to the coil 53 to 100 heat the terminal member 51 to the required temperature by connecting a source of such current to the leading-in conductor 52 and to the conductor 54. The conductor 54 may be suitably insulated from the conductor 52, as for example, by a small glass tube as indicated at 55. It will be apparent that the arrangement of Fig. 6 represents a modification of the arrangement of Fig. 1 which 105 still utilizes the principle of providing a loop through which heating currents may be passed to bring relatively large size terminal members up to the requisite temperature during exhausting. It will be understood, however, that the arrangement in Fig. 6 is diagrammatically illustrated and not 110 accurately drawn to scale.

115 It will be apparent that the principles of my invention may be applied to high vacuum direct current fuses as well as high vacuum alternating current fuses since in each case it is highly important to de-gas the terminals very thoroughly. Where very large currents are to be broken by direct current fuses it 120 is desirable to use several fuse links or fuses 125 130

in parallel as heretofore described, in order to reduce the duty on the fuse and make proper operation more certain.

In certain relations of utility, apparatus is involved which operates at times on alternating current and at other times on direct current. An example of such apparatus is an electric locomotive which is arranged so as to operate during a part of its journey from an alternating current trolley or third rail, and during other times from a direct current supply. To protect apparatus under such circumstances it is desirable to connect two fuses in series, one fuse being of the high vacuum alternating current type and the other of the high vacuum direct current type. Such an arrangement is diagrammatically indicated in Fig. 7 wherein 56 indicates a device to be protected and 57 and 58 are respectively fuses of the direct current and alternating current type. With such an arrangement the circuit will be protected whether the excess current occurs with an alternating current or a direct current, one or the other fuse being sure to interrupt the circuit even though the other does not.

From the foregoing description it is apparent that my invention is applicable to fuses of many sizes and to fuses for circuits of widely different voltages. The fuse is so simple and so comparatively inexpensive when considered with relation to oil circuit breakers of a capacity adequate to interrupt lines subject to excessive overloads, such as short circuits, that I anticipate that the high vacuum fuse will have a considerable field of application as a substitute for or as an auxiliary protective device for use with switches such as oil switches.

Suitable disconnecting switches will be provided on each side of the high vacuum fuse so that when the fuse has broken the circuit, the terminals may be killed and a new fuse safely inserted. Such disconnecting switches are well known and may be either directly operated or remotely controlled. Automatic mechanism may be provided for substituting a new fuse when one fuse has blown and such mechanism may, if desired, be provided to insert fuses a predetermined number of times in succession, say for example three times, and if the overload still persists the mechanism may lock out as is frequently done in the case of automatic reclosing circuit breakers.

With reference to the use of high vacuum fuses as an auxiliary protection for oil switches I have proposed a combination of apparatus which enables a much smaller oil switch to be used and still produce a safe and economical arrangement for insuring that the circuit shall be cleared in case of an overload such as a short circuit. Oil switches for feeder and line protection, for example, are customarily made a great deal larger than is

necessary for normal operation. The greater number of operations of the switch will take place on relatively small currents which could be broken by a relatively small and inexpensive oil switch but owing to the fact that the circuit must be cleared in case of excessive overload such as a short circuit the switch must be made a great deal larger and consequently a great deal more expensive than its normal service requires. I propose to employ a high vacuum fuse in series with the oil switch and rely upon the fuse to break the circuit in case the oil switch fails to do so. I can thus use an oil switch which is of the proper size to take care of normal operation and rely upon the fuse to take care of abnormal conditions. According to one arrangement I propose to use an oil switch or suitable quick acting air break switch in shunt with the fuse so that the fuse will be short circuited when this switch is closed. When the circuit is to be interrupted the oil switch in series with the fuse will open first. After this oil switch has opened, its mechanism will be arranged to cause the opening of the switch in shunt with the fuse. If the series switch clears the circuit, the fuse will, of course, carry no current. If, however, the oil switch fails to clear the circuit the opening of the second switch will put the fuse in circuit and this will blow and clear the circuit after which the series oil switch may be repaired and a new fuse inserted. As thus arranged the switch in shunt to the fuse would have little duty to perform and it also could be relatively inexpensive. If desired, the switch in shunt to the fuse may be arranged so that it does not open its contacts unless the oil switch fails to clear the circuit. To accomplish this mode of operation several expedients may be provided. For example, the switch in parallel with the fuse may have its trip coil in series relation with the circuit to be protected but have that trip coil short circuited when the series oil switch is closed. When the series oil switch opens, the short circuit will be removed from the trip coil of the switch which shunts the fuse and, if the current is still flowing, the trip coil will be energized and cause the switch to open thereby inserting the fuse. In order to give time for the oil switch to clear the circuit, the operation of the trip coil for the switch shunting the fuse may be retarded by suitable means, examples of which are well known in the art of circuit breakers and oil switches.

The arrangement of the fuse and two switches above described is diagrammatically shown in Fig. 8, where the oil switch for normally controlling the circuit is indicated at 59. The high vacuum fuse is indicated at 60, and the switch in shunt with the fuse is indicated at 61.

While I have described particular embodiments of my invention and particular circuit

arrangements in which the fuse may be used it will be apparent to those skilled in the art that changes and modifications may be made without departing from my invention and I therefore aim in the appended claims to cover all such changes and modifications as fall within the true spirit and scope of my invention.

What I claim as new and desire to secure 75
10 by Letters Patent of the United States is:

1. A high vacuum fuse comprising an evacuated vessel, a pair of metal terminals within said vessel, a fusible element connected in series with said terminals, said terminals each 80
15 being in the form of a loop, two sides of the loop terminating each in a leading-in wire extending through the walls of the vessel.

2. A high vacuum fuse comprising a vessel, spaced terminals therein and a fuse link 85
20 mounted between said terminals each terminal comprising a hairpin shaped loop with the legs of each loop extending through the walls of the vessel and sealed therein with a vacuum tight seal, said terminals being relatively 90
25 large with respect to the fuse link, said terminals and fuse link and the inner walls of said vessel and all other metal parts within the vessel being thoroughly freed of occluded gas and the vacuum being as high as it is 95
30 practicable to attain and at least as high as one one-hundredths of a micron.

3. A fuse comprising a vessel, a pair of terminals located within the vessel, a fusible element located between said terminals, and a 100
35 pair of leading-in wires extending through the walls of said vessel to each of said terminals whereby each terminal may, independently of the fusible element, be heated whereby occluded gases may be driven off from 105
40 said terminals.

4. A fuse comprising a vessel, a pair of terminals located within said vessel, a fusible element within said vessel connected in series with said terminals, and a pair of leading-in 110
45 wires extending through the wall of said vessel and terminating in one of said terminals whereby said terminal may be heated, independently of the other terminal by applying a source of current across said leading-in 115
50 wires.

5. A high vacuum fuse comprising a vessel, spaced terminals within the vessel, a plurality of fuse links supported between said terminals, connections to said terminals extending 120
55 through the walls of the vessel permitting current to be conducted to said terminals at a plurality of points, said vessel being exhausted to an extremely high degree of vacuum and all parts within the vessel being 125
60 thoroughly freed of occluded gases.

6. The combination of a circuit to be interrupted, fuse means for interrupting said circuit comprising a plurality of fuse links in parallel, each fuse link being located in a 130
65 high vacuum and means for controlling the

division of the circuit current between said fuse links.

In witness whereof, I hereunto set my hand this 14th day of March, 1928.
